[57] **CLAIM**

The ornamental design for a liquid crystal display for a modem enclosure, as shown and described.

DESCRIPTION

FIG. 1 is a left perspective view of a liquid crystal display for a modem enclosure;

FIG. 2 is a right perspective view thereof;

FIG. 3 is a top view thereof; and,

FIG. 4 is a front view thereof.

The broken line showings of a modem enclosure throughout the drawings are for illustrative purposes only and form no part of the claimed design.
